UNITED STATES PATENT OFFICE.

JOHN A. CHAMBERS, OF NEWBURG, MISSOURI.

APPARATUS FOR RECEIVING AND DELIVERING MAIL.

1,150,340.

Specification of Letters Patent.

Patented Aug. 17, 1915.

Application filed August 12, 1914. Serial No. 856,402.

To all whom it may concern:

Be it known that I, JOHN A. CHAMBERS, a citizen of the United States, residing at Newburg, in the county of Phelps and State 5 of Missouri, have invented a new and useful Apparatus for Receiving and Delivering Mail, of which the following is a specification.

This invention relates to apparatus for receiving and delivering mail, it being designed more especially for effecting the interchange of mail between a moving car and stations along the route thereof.

One of the objects of the invention is to provide a novel means for ejecting bags or other mail containers, said means being so constructed as to operate easily without undesirable pounding or too sudden starting, no matter at what speed the car may be 20 traveling.

A further object is to provide novel means for shifting the mail receiver outwardly away from the passing car as soon as the interchange of mail has been effected.

25 Another object is to provide a novel form of mail projecting mechanism which can be easily swung to active position outside of a car and shifted back into the car.

With the foregoing and other objects in view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of the mechanism constituting the present invention, a portion of a car being shown in section, the various parts being shown in the positions assumed thereby immediately prior to effecting the interchange of mail, the positions to which the parts are moved subsequent to the interchange of mail, being indicated by dotted lines. Fig. 2 is a side elevation of a portion of a car having the present improvements combined therewith, the said mechanism being partly in section, the section being on the line 50 A—B Fig. 1. Fig. 3 is a section on line

C—D Fig. 1. Fig. 4 is a section on line E—F Fig. 3. Fig. 5 is a plan view of one of the mail holders and ejectors. Fig. 6 is a rear elevation of one of the cams and showing its controlling spring. Fig. 7 is an 60 enlarged vertical transverse section through the basket or receiver. Fig. 8 is a vertical transverse section through certain of the tripping bars and showing one of their supporting brackets. 65

Referring to the figures by characters of reference 1 designates a car structure having a door opening 2, and pivoted within this door opening so as to extend from one side to the other thereof is a basket or receiver 3, the bottom of which is in the form of a grate, as shown at 4, this grate being overhung by a curved top 5 preferably made of heavy metal fabric. The ends of the basket are preferably closed by means of 75 a like material while the front or outer side of the basket is open. This basket is adapted to be held in raised or active position in any suitable manner, it being preferably counterbalanced by means of a weight 6 80 provided along the front thereof. When, however, an article such as a mail bag or the like is thrown into the basket, the weight 6 will be overbalanced and the rear portion of the basket will swing downwardly. 85

Secured upon the outer side of the car structure 1 adjacent the front or advancing side of the door opening, are tripping bars 7 preferably parallel, these bars being provided at their rear ends with substantially horizontal portions 8 close to the opening 2, these horizontal portions merging into parallel upwardly inclined portions 9 which, in turn, merge into forwardly diverging portions 10. These bars 7 can be connected to the car structure in any suitable manner, as by means of yokes 11 outstanding from said structure. 90

Secured to the outer side of the car structure 1 adjacent that side of the opening 2 remote from the bars 7 is a bracket 12 having a seat 13 at its upper end formed by cutting away one side of a socket formed in the end of the bracket. An arcuate brace 14 105 connects the bracket 12 to the car structure 1 and has a supporting arm 15 extending horizontally therefrom toward the opening 2.

An L-shaped arm 16 is pivotally connect- 110

ed to the inner side of the car structure close to the door opening 2 and is adapted to swing into the opening so as to project outwardly at right angles to the side of the car 5 or to swing inwardly from said opening so as to be supported entirely within the car. This arm has an extension 17 at its outer end to which is fixedly connected a frame 18 having a shaft 19 journaled therein, said 10 shaft being parallel with the arm 16. The outer end of the shaft has a crank arm 20, and fixedly connected to the shaft, so as to rotate within the frame 18 is a cam 21. A lever 22 is fulcrumed on the frame 18 and 15 is adapted to swing in a substantially horizontal plane, the fulcrum of this lever being arranged in a vertical plane extending through the center of the cam 21 and the two arms of the lever constantly bearing 20 against diametrically opposed portions of the cam 21. When the arm 16 is extended outwardly from the door opening 2, one of the arms of lever 22 is extended forwardly or in the direction in which the car 1 is 25 moving and this forwardly extending arm of lever 22 is fixedly connected to a box 23 open at the front, top and back and having guide flanges 24 extending inwardly from its sides. A follower 26 is slidably mounted 30 in the box and is held against displacement relative thereto by the flanges 24.

Fixedly connected to the inner end portion of the arm 16 is a tongue 27 and the end of this tongue, which is located directly 35 back of the box 23, is connected by a link 28, to one end of a lazy tongs 29. This lazy tongs is extended into the box 23 and is connected to the follower 26, one of the pivots of the lazy tongs where two of the members 40 thereof cross, being connected to the box 23 by a pivot rod 30.

A spiral spring 31 is secured at one end to the back face of the cam 21 and at its other end to the frame 18, this spring serving 45 to hold the cam 21 and the crank arm 20 normally in predetermined positions. In other words, should the crank arm 20 be shifted out of its normal position, it will be promptly returned by spring 31 to its initial 50 position, when released.

The apparatus used at each station where the interchange of mail is to be effected includes rails 32' extending at right angles from the track on which the car 1 is adapted 55 to travel, and these rails are engaged by wheels 32 located under and supporting a box-like receiver 33 which is open at its front and top. A coiled spring 34 is secured at one end to the bottom of the receiver 33 and at its other end to a supporting structure 35 on which the rails 32' are mounted, this spring serving to hold the receiver normally pulled away from the track on which 60 the car 1 travels. A lever 36 is connected to the back portion of the receiver 33 and its

lower end is designed to engage a keeper 37 on the structure 35. The upper end of the keeper is detachably engaged by an eye 38 formed at one end of a lever 40 fulcrumed on the receiver 33, said lever, in turn, being 70 engaged by one end of another lever 41. This second lever, which is mounted on the receiver 33 is adapted to be actuated by a crank arm 42 extending from the inner end of a shaft 43 journaled on the receiver 33, 75 said shaft 43 having a depending arm 44 supported in front of the open or receiving face of the receiver 33.

Secured to the receiver 33 adjacent that end of its open face nearest the approaching car 1, are outstanding brackets 45 in the form of yokes supporting parallel bars 46 similar to the bars 7 hereinbefore referred to, these bars 46 being parallel at that end nearest the open face of the receiver 33. 80 These parallel portions 47 merge into upwardly inclined portions 48 which, in turn, merge into diverging end portions 49 so positioned that, when the receiver 33 is locked in active position, the end of the crank arm 20 extending outwardly from the car will be received between these diverging portions 49, as shown in section in Fig. 3. The arm 44 extends downwardly across the bars 47 so as to be engaged and shifted by the arm 20 95 as said arm 20 passes from between the bars 46. This actuation of the arm 44 will of course rock the shaft 43 and cause the crank arm 42 to shift lever 41. This will result in the elevation of the eye 38 and the release 100 of lever 36 from its keeper 37. Consequently the spring 34 which is under tension, will quickly shift the receiver 33 outwardly away from the track on which the car 1 is traveling. 105

Mounted on the receiver 33 above the open face thereof is a frame 50 in which is journaled a shaft 51 which is parallel with the rails 32' and is provided, at its outer or free end with a crank arm 52 designed, as a car passes the apparatus, to enter between the diverging portions 10 of the bars 9 on the car. This shaft 51 has a cam 53 fixedly connected to it and fulcrumed within the frame 50 and in front of the cam 53 is a lever 54 constantly bearing against the cam at substantially diametrically opposed points. Fixedly connected to each end of the lever 54 with the cam 53 interposed between them, are box-like holders 55 similar to the holders 23 hereinbefore described, each of these holders containing a follower 56 to which is secured one end of a lazy tongs 57. One of the pivots of the lazy tongs is connected to the box 55, as shown at 58 and the inner end of the lazy tongs is connected by a link 59 to the fixed portion of the receiver 33. As shown particularly in Fig. 1 115 the two boxes 55 converge outwardly. 120

In order to reduce frictional engagement 130

between the levers 22 and 54, and the respective cams 21 and 53, anti-friction rollers 60 may be provided on these levers for bearing against the cams.

5 Assuming that an interchange of mail is to be effected at a station, the bag or other container with the mail therein and which is to be delivered to the station, is placed in the holder 23 after the follower 26 has been drawn back to the inner end portion 10 of the holder. The arm 16 with all the parts supported thereby is then swung outwardly to a position at right angles to the car 1, thus bringing the end of its extension 17 into position upon the seat 13, as shown in Fig. 2. The mail to be delivered to the car is placed in the holder 55 nearest the approaching car, the follower 56 in said holder being first retracted by adjusting lever 54 20 so as to have said holder in its innermost position. The receiver 33 is adjusted toward the track on which the car 1 is traveling and is secured by placing the lower end of lever 36 in engagement with keeper 37 and by placing the eye 38 in engagement with the upper end of lever 36. With the parts thus positioned, car 1, when passing the station, causes the diverging ends 10 of the bars 9 to receive between them the crank 30 arm 52. While this crank arm is so positioned, the crank arm 20 carried by the car is passing into position between the diverging ends 49 of the bars 46. As crank arm 20 moves into position between the inclined 35 portions 48 of the bars it will cause a rotation of the shaft 51 and, consequently, the cam 53 will be rotated against the action of its spring 31 so as thus to swing the lever 4 and cause the holder 55 which is nearest 40 the approaching car to swing outwardly toward the car just as the door opening 2 is passing the holder 55. At the same time the pivot 58 will pull on the lazy tongs 57 and cause said tongs to elongate quickly, thus 45 to shift the follower 56 longitudinally within the holder 55 and eject from the holder and through the door opening 3 the bag or other mail containing receptacle to be delivered. This receptacle will be received 50 within the basket 3 and will overbalance the weight 6 so that said basket will swing downwardly within the car without danger of the mail falling out of the car and onto the track. As soon as the crank arm 20 passes between the parallel portions 47 of the bars 46, it will strike the arm 44 and release the receiver 33 as hereinbefore described, so that said receiver will thus be 55 drawn automatically away from the car. 60 While the foregoing operation is taking place the crank arm 52 is being rotated by the bars 7 so that the cams 21 actuate lever 22 and cause the holder 23 to swing toward the receiver 33 and the follower 26 to shift 65 longitudinally within the holder 23, thus to

suddenly eject the contents of the holder 23 and cause them to fall into the receiver 33 prior to the release of said receiver after the interchange of mail has been effected. The arm 16 with the parts supported thereby can be swung back into the car 1 as shown by dotted lines in Fig. 1.

70 Although the basket 3 has been shown located in the upper portion of the door opening 2, it is to be understood that it can be located in the lower portion of the said opening and the other parts of the apparatus can be readjusted accordingly.

75 Importance is attached to the fact that the mail is delivered from the track along diagonal lines so that the mail will be discharged in a direction opposite to that in which the train is moving. Consequently the velocity of the train is to an extent overcome and the mail will be accurately delivered.

80 It will be noted that by mounting each holder and its follower in the manner shown and described, the said follower will be shifted in the same direction as the holder by the actuation of said mechanism, but at a 85 greater speed than the holder. For example, when the lever 54 is swung so as to shift the holder 55 toward the car, said holder will pull, through the pivot 58, upon the lazy tongs 57 which are anchored by the links 59. 90 Consequently the links of the lazy tongs will constitute speed multiplying means whereby the follower 56 will be moved longitudinally within the holder 55 toward the outlet end of said holder and in the same direction in 95 which the holder is moved by the lever 54.

100 What is claimed is:

1. In an apparatus of the class described, the combination with a holder, a follower therein, and means for shifting the holder longitudinally, of speed multiplying means 105 operated by the longitudinal movement of the holder for moving the follower positively in the same direction as the holder but at a greater speed.

110 2. In an apparatus of the class described, the combination with a holder open at its ends, a support therefor, and means for shifting the holder outwardly relative to the support, of a follower within the holder, and speed multiplying means operated by the outward movement of the holder for shifting the follower positively outwardly at a higher speed than the holder.

115 3. The combination with a holder, a support therefor, and means for shifting the holder in the direction of its length outwardly relative to the support, of a follower within the holder, a lazy tongs connected to the follower and to the holder, and a connection between the lazy tongs and the support whereby, during the outward movement of the holder, the follower is projected outwardly faster than the holder.

120 4. The combination with a lever, a holder 130

fixedly mounted thereon and having open ends, a follower within the holder, a supporting structure, and means operated by the movement of the holder relative to the supporting structure for projecting the follower in the same direction with the holder but at a higher speed, of a revoluble lever actuating element, a crank arm movable therewith, and means for engaging the crank arm to rotate said element to actuate the lever.

5. The combination with a supporting structure, a lever thereon, a holder fixedly connected to the lever and having an open end, a follower within the holder, and means operated by the movement of the follower relative to the supporting structure for projecting the follower in the same direction with said holder but at a higher speed, of revoluble means for shifting the lever, a crank arm movable with said means, and spaced inclined members for receiving the crank arm therebetween to rotate said element.

25 6. The combination with a cam mounted for rotation, a crank arm movable therewith, and a deflecting element for engagement with the crank arm to rotate the cam, of a holder having an open end, means operated by the cam for shifting the holder longitudinally, a follower within the holder, and means operated by the movement of the holder for shifting the follower in the same direction as the holder but at a greater speed.

7. The combination with a cam mounted for rotation, a crank arm movable therewith, and a deflecting element for engagement with the crank arm to rotate the cam, of a holder having an open end, means operated by the cam for shifting the holder longitudinally, a follower within the holder, means operated by the movement of the holder for shifting the follower in the same direction as the holder but at a greater speed, and means for automatically returning the cam and holder to their initial positions when the crank arm becomes disengaged from the deflecting means.

50 8. The combination with a receiver movably mounted, and means for holding the receiver normally in a predetermined position, of a cam mounted for rotation, a crank arm revoluble therewith, a holder having an open end, means operated by the cam for shifting the holder in the direction of its length outwardly away from the receiver, a follower within the holder, and means operated by the movement of the holder relative to the follower for shifting said follower in the same direction as the holder but at a greater speed.

9. The combination with a receiver movably mounted, and means for holding the

receiver normally in a predetermined position, of a cam mounted for rotation, a crank arm revoluble therewith, a holder having an open end, means operated by the cam for shifting the holder in the direction of its length outwardly away from the receiver, a follower within the holder, means operated by the movement of the holder relative to the follower for shifting said follower in the same direction as the holder but at a greater speed, and deflecting means in the path of the crank arm for rotating said arm and the cam.

10. The combination with a receiver movably mounted, and means for holding the receiver normally in a predetermined position, of a cam mounted for rotation, a crank arm revoluble therewith, a holder having an open end, means operated by the cam for shifting the holder in the direction of its length outwardly away from the receiver, a follower within the holder, means operated by the movement of the holder relative to the follower for shifting said follower in the same direction as the holder but at a greater speed, deflecting means in the path of the crank arm for rotating said arm and the cam, and means for returning the cam and holder to their initial positions when said arm becomes disengaged from the deflecting means.

95 11. The combination with a receiver movably mounted, and means for holding the receiver normally in a predetermined position, of a cam mounted for rotation, a crank arm revoluble therewith, a holder having an open end, means operated by the cam for shifting the holder in the direction of its length outwardly away from the receiver, a follower within the holder, means operated by the movement of the holder relative to the follower for shifting said follower in the same direction as the holder but at a greater speed, and spaced deflecting members in the path of the crank arm and adapted to receive said arm therebetween to rotate the arm and cam during the movement of the arm between said deflecting members.

100 12. The combination with a movably supported receiver, yielding means for holding the said receiver normally in a predetermined position, and a holding element for securing the receiver against movement under the action of said means, and means for releasing said element, and a deflecting device upon the receiver and extending past the releasing means, of a car supported structure, a holder movably mounted thereon, a cam, a crank arm revoluble with the cam and movable successively into engagement with the deflecting device and releasing means thereby to successively rotate the cam and release the receiver, means operated by the cam for shifting the holder toward

the receiver, a follower within the holder, and means operated by the movement of the holder relative to the car supported structure for shifting the follower in the same 5 direction as the holder but at a greater speed.

In testimony that I claim the foregoing

as my own, I have hereto affixed my signature in the presence of two witnesses.

JOHN A. CHAMBERS.
